LOCK

Joseph H. Milligan, Framingham, Mass., assignor
of twenty-five one-hundredths to Jeremiah
McGillicuddy and Patrick McGillicuddy, Bos-
ton, Mass.

Application November 17, 1937, Serial No. 175,050

21 Claims. (Cl. 70—143)

This invention relates to locks for doors and it has for one of its objects to provide a novel lock in which a single locking element functions both as a spring latch and as a locking or dead bolt.

5 A further object of the invention is to provide a novel lock of this type in which the axial line of the combined latch and locking bolt intersects the axial line of the operating spindle.

10 A still further object of the invention is to provide a novel lock of this type in which the operative parts are confined within a small compass, thus making it necessary to cut a relatively small cavity in the door to receive the lock.

15 A still further object of the invention is to provide a novel lock of this type which is "jimmy" proof.

A still further object of the invention is to provide a lock of this type which can be used 20 equally well for doors of residences or for automobile doors and in a variety of other places.

Other objects of the invention are to improve generally locks of this invention in the particulars hereinafter set forth.

25 In the drawings wherein I have illustrated some embodiments of the invention,

Fig. 1 is a horizontal sectional view through a portion of a door showing my improved lock installed therein;

30 Fig. 2 is a section on the line 2—2, Fig. 1;

Fig. 3 is a section similar to Fig. 5 but showing the door locked;

35 Fig. 4 is a section similar to Fig. 2 but showing the door unlocked and the combined latch and locking bolt withdrawn;

Fig. 5 is a section through the combined latch and bolt member on the line 5—5, Fig. 3;

Fig. 6 is a section on the line 6—6, Fig. 4;

40 Figs. 7 and 8 are sections on the line 7—7, Fig. 4, showing the safety device in different positions;

Fig. 9 is an inner end view of the locking bolt showing the bolt actuator in section;

45 Fig. 10 is a fragmentary sectional view illustrating the initial step in withdrawing the locking bolt from the keeper when the door is to be unlocked;

Fig. 11 is a fragmentary sectional view showing how my improved lock may be applied to an automobile door;

50 Fig. 12 is a section on the line 12—12, Fig. 11;

Fig. 13 is a fragmentary sectional view showing the operation of the combined latch and locking member when the door is being closed.

55 In Figs. 1 to 10, 1 indicates the portion of a

door and 2 is a portion of the door jamb or door frame, the latter having the usual cavity 3 to receive the locking element and also being provided with the usual striker or keeper 4 which is shown as secured to the door jamb by means of suitable screws 5. The combined latch and locking bolt is shown at 6 and it is mounted in a suitable casing or housing 7 which is received in a cavity in the door 1 provided for that purpose.

8 indicates the knob spindle which extends 10 through the door and which is provided with the knobs 9 and 10. In Fig. 1 the knob 9 is the knob on the inside of the door and is made fast on the spindle 8, while the knob 10 is the outside knob on the outside of the door. Any suitable operating 15 connection between the outside knob 10 and the spindle 8 may be employed, but I prefer to use a key-controlled operating connection such as shown in my co-pending application, Serial No. 84,446, filed June 10, 1936, now Patent No. 20 2,119,866, June 7, 1938. The operating connection shown in said application is such a construction that normally the outside knob is locked from turning movement but can be unlocked by the insertion of a key in a suitable key slot 25 formed in the knob. The unlocking of the outer knob by insertion of the key permits it to be turned, and the turning movement thereof is transmitted to the spindle by suitable mechanism. The lock for the outer knob, however, does 30 not interfere with the turning of the spindle at any time by means of the inner knob 9.

The connection between the spindle 8 and the combined latch and locking bolt 6 is such that when the door is swung into a shut position the 35 combined latch and locking bolt 6 is free to move backwardly into the door against the action of a spring as it strikes the striker 4 and without giving any rotary movement to the spindle 8, said spring thus allowing the door to close, and when 40 the door has been closed said spring operates automatically to throw the bolt 6 forwardly into door-latching position in the opening 32 of the striker as shown in Fig. 2, also without giving movement to the spindle 8 or the knob 9.

45 The operative connection between the spindle 8 and the bolt 6, however, is such that by turning the knob 9 in one direction said bolt may be withdrawn from the striker to open the door, 50 and by turning the knob in the other direction the bolt may be thrown forwardly into a locking position in which said bolt becomes a deadlock for locking the door. Furthermore, the bolt is constructed so that when it is in the latter or 55

locking position the lock is practically "jimmy" proof.

The operative connection between the spindle 8 and the combined latch and locking bolt 6 includes a pinion 11 which is fast on the spindle 8 and a rack 12 which is situated within the housing 7 and meshes with the pinion 11. The forward end of the rack 12 is bent downwardly to form a lip 13 which normally engages between a plate 14 at the inner end of the locking bolt 6 and an abutment pin 15 which is carried by said bolt. With this connection the turning of the pinion 11 clockwise in Fig. 2 will move the rack 12 to the right, and the engagement of the lip 13 against the plate 14 will serve to move the bolt 6 to the right, thus withdrawing it from the striker 4 as shown in Fig. 4.

The turning of the spindle 8 in a counter-clockwise direction, Fig. 2, will move the rack 12 to the left, and the engagement of the lip 13 with the pin 15 will move the bolt forwardly into a position shown in Fig. 3 in which the door is deadlocked. 19 indicates a spring acting on the bolt 6 and tending to move it forwardly. One end of this spring is received in a cavity 20 formed in a bolt 6 and the other end encircles a guide pin 21 which is anchored in and extends from the housing 22 for the pinion 11.

To provide for backward movement or retracting movement of the bolt 6 against the action of the spring 19 without giving turning movement to the spindle 8 and knob 9 when the bolt 6 functions as a spring latch, I provide means for retracting the pin 15 and moving it inwardly to disengage it from the lip 13 at such time as the end of the bolt engages the striker when the door is swung shut.

The plate 14 above referred to is carried on the end of a pin 18 which is mounted axially in the bolt 6 and is capable of longitudinal movement therein. This pin is cut away on one side at 23 and is formed with the cam surface 24 with which the abutment pin 15 cooperates, said pin being acted on by a spring 25 which tends to move it inwardly. This releasing pin 18 extends through the bolt 6 and the outer end thereof is pivotally connected at 26 to a feeler element 27 which operates in a slot 28 formed in the end of the bolt 6 and which is acted on by a spring 29 that normally holds it projected somewhat beyond the inclined end face 30 of the bolt 6, as best seen in Fig. 1. When the door is swung shut the inclined face 31 of the feeler 27 will engage the striker and said feeler will be pushed inwardly into the slot 28 and into a position flush with the face 30 of the bolt. Such inward movement of the feeler 27 moves the releasing pin 18 inwardly relative to the bolt and brings the pin 18 into the position relative to the bolt shown in Fig. 13. As the pin 18 is thus moved toward the right the low portion of the recess 23 is brought underneath the abutment pin 15 and the spring 25 forces said abutment pin inwardly into a position where its end is below the tip of the lip 13. As soon as the abutment pin reaches this position, then the operative connection between the bolt 6 and the neck 17 of the rack 12 is disrupted and the bolt is free to be moved backwardly or inwardly against the action of the spring 19 by the engagement of the inclined face 30 of the bolt with the striker 4 so as to allow the door to close. As soon as the door is closed the bolt will register with the opening 32 in the striker 4 and the spring 19 will then force the bolt forwardly through said opening 32 and into the latching

position shown in Fig. 2. When the bolt comes into register with the opening 32 of the striker the pressure on the feeler 27 will be relieved and the spring 29 will then tend to force said feeler forwardly to restore the releasing pin 18 to its normal position shown in Fig. 2.

Means are provided, however, to hold the releasing pin in its retracted position until the bolt 6 has completed its forward movement into the latching position shown in Fig. 2 wherein the abutment pin 15 is located immediately in front of the lip 13 of the rack 12. The bolt 6 is provided with an auxiliary latch 38, which is used for making the lock "jimmy" proof as will be presently described, and which operates in a recess 39 extending transversely of said bolt. This auxiliary latch 38 is formed with a stem or body portion 40 which operates in a recess or cut-away portion 41 with which the releasing pin 18 is provided in one side. Said auxiliary latch is also formed on its inner end with a wedge-shaped head 41 and is backed by a suitable spring 42 which tends to throw it outwardly into a position projecting beyond the side of the bolt 6.

The pin 18 is formed on one side with a V 25 notch 43 of a shape and size to receive the head 41, and said pin 18 is formed on its opposite side with a second notch 44 that cooperates with a screw-threaded pin 45 carried by the auxiliary latch 38, said notch 44 having a dip or recess 46 in its bottom.

The two notches 43 and 44 are out of line with each other and have such relative positions that when the releasing pin is in its forward position shown in Fig. 2, the notch 43 is in line with the head 41, while when the pin 18 is in its retracted position shown in Fig. 4 the notch 44 is in line with the pin 45.

The housing 7 is provided with an aperture 47 in which the auxiliary latch 38 is received when the bolt is in its latching position, the engagement of the latch 38 in said aperture normally preventing the bolt 6 from being moved backwardly. When the pin 18 is moved backwardly by reason of the feeler 27 engaging the striker 4, the inclined wall of the notch 43 in said pin will have a camming action on the head 41 and will force the latter backwardly into the position shown in Fig. 13, and this movement of the head 41 will cause the auxiliary latch 38 to be withdrawn from the opening 47 into its recess 39 also as shown in Fig. 10. The bolt 6 is then free to move backwardly and as it moves backwardly the auxiliary latch 38 is held in its depressed position by engagement of the inner 55 wall of the housing 7. The auxiliary latch 38 is provided with an inwardly projecting pin 45 which is seated in the bottom of the recess 44 when the auxiliary latch is in its retracted position (see Fig. 10) and so long as the auxiliary latch is thus held retracted the releasing pin 18 will be locked from forward position by the pin 45. The releasing pin will thus be held in its retracted position during the backward movement of the bolt 6 which takes place when the latch engages the striker 4 during the shutting of the door and said pin 18 will also be held in its retracted position until the bolt 6 moves forwardly into its latching position shown in Fig. 2, in which position the auxiliary latch registers 70 with the opening 47. The abutment pin 15 will be held in its lowered position by the spring 25 during the entire time that the releasing pin is held retracted by the pin 45 of the auxiliary latch and, therefore, the abutment pin is prevented 75

from moving outwardly into its operative position until after the bolt 6 has been returned to its latching position, in which position the abutment pin will be located immediately in front 5 of the lip 13 so that when the abutment pin resumes its normal position it will be properly located with reference to the lip 13.

The operative connection between the spindle 8 and the bolt 6 is thus automatically disrupted 10 when said bolt 6 is functioning as a spring latch, and is then automatically re-established again when the bolt 6 springs into the opening 32 of the striker 4.

As stated above, the door is opened by turning 15 the spindle 8 in a clockwise direction to move the rack 12 toward the right, during which movement the lip 13 acts on the plate 14 to pull the bolt inwardly. The pulling action of the lip 13 on the plate 14 will first move the pin 18 within 20 the bolt 6 for a short distance to bring the pin 18 into the position relative to the bolt shown in Figs. 4 and 10, and during this operation the abutment pin 15 will be moved inwardly by its spring 25. After the releasing pin 18 has been 25 moved into the position relative to the bolt shown in Fig. 4, then further pulling action of the rack 12 and lip 13 on the plate 14 will move the bolt 6 inwardly or to the right, thereby releasing it from the striker 4 so that the door may be 30 opened. During the retracting movement of the bolt 6, and while the rack 12 is applying thereto a force tending to move it to the right, Fig. 4, the releasing pin 18 will have the position shown in Fig. 4 and the abutment pin 15 will be held 35 in its lowered position by its spring 25. In order to maintain the operative connection between the lip 13 of the rack and the bolt it is necessary that the abutment pin 15 should be projected outwardly into the dotted line position, Fig. 4, or the 40 full line position, Fig. 3, as soon as the knob is released so that the lip 13 will maintain its operative position between the plate 14 and said pin 15.

The housing 7 is provided with an aperture 49 45 with which the auxiliary latch 38 registers when the bolt is in its retracted position shown in Fig. 4. As soon as the knob is released after having retracted the bolt the spring 29 acting on the feeler 27 immediately throws said feeler and the releasing pin 18 forwardly into the position relative to bolt 6 shown in Figs. 2 and 3, thereby causing the cam surface 24 to act on the abutment pin 15 and move the latter upwardly against the action of its spring 25. the return of the spindle 8 and knob 9 to its initial position when the knob has been released. This additional spring 33 is confined between a driver 34 at the inner end of the housing 7 and a member 35 which is slidably mounted within the housing and is provided with an abutment 36 against which the end of the rack 12 is adapted to abut. This member 35 is shown as having a recess 37 in which the inner end of the spring 33 is received. When the knob is turned to withdraw the combined latch and bolt 6 from the striker as shown in Fig. 4, the engagement of the end of the rack 12 with the abutment 36 forces the member 35 backwardly within the housing against the action of the spring 33, as shown in Fig. 4, and when the knob is released the expanding of the two springs 19 and 33 serve to move the bolt 6 forward and to bring the rack 12, spindle 8 and knob 9 back into their initial position.

The auxiliary latch 38 above referred to serves to render the lock "jimmy" proof by preventing the bolt from being withdrawn from the striker by the use of a "jimmy" when said bolt is in the deadlocking position shown in Fig. 3. When the releasing pin 18 is in its forward position, as shown in Figs. 2 and 3, the spring 42 will force the auxiliary latch 38 outwardly and will bring the head 41 into the notch 43. When the releasing pin 18 is moved to the right into the position shown in Figs. 4 and 10, then one side of the notch 43 comes against the wedge-shaped head 41 and forces said head downwardly against the action of the spring 42 thereby withdrawing the auxiliary latch 38. The outer face 46 of the auxiliary latch 38 is beveled or inclined and when the bolt 6 is in its latching position shown in Fig. 2 the auxiliary latch 38 occupies an opening 99 in the housing and the inclined face 46 of said latch rests against the inclined face 47 of the head 48 of the housing 7. The auxiliary latch 38 thus prevents the bolt from being pushed inwardly by application of force directly to its beveled end face 30. When the bolt 6 is moved forwardly from the latching position to the locking position the engagement of the inclined face 46 of the auxiliary latch with the inclined face 47 of the head 48 of the housing 7 will allow it to pass through the head 48 and through the opening 32 in the striker 4. As soon as the bolt 6 reaches the locking position shown in Fig. 3 the auxiliary latch 38 is moved outwardly behind the striker by the spring 42. This auxiliary latch thus locks the bolt in the striker and prevents it from being withdrawn by the insertion of a jimmy between the door and the striker. When the door is to be unlocked the knob is turned to turn the spindle 8 clockwise in Fig. 3, and the initial movement to the right which is given to the rack 12 will move the head 41 backwardly from the bolt and thus move the releasing pin 1

bolt from being pushed inwardly by the application of pressure directly to the beveled end face 30 thereof. If, however, pressure is applied to the feeler 27 and the latter is pushed inwardly 5 this will result in moving the releasing pin 18 backwardly relative to the bolt 6 into the position shown in Fig. 4, and during such backward movement of the releasing pin 18 the inclined face of the notch 44 will have a camming action 10 against the head 41 thereby retracting the auxiliary latch and thus unlocking the bolt so that it can be pushed inwardly into the door. This same backward movement of the releasing pin 18 removes the cam face 24 from the inner end of the 15 abutment pin 15 so that said pin moves inwardly under the influence of the spring 25. Continued manual pressure on the feeler 27 will then move the bolt 6 inwardly without giving movement to the rack 12, the depressed abutment pin 15 during such movement passing under the lip 13 of the rack 12.

I have provided herein means whereby if this occurs the operative relation between the bolt and the rack 12 will not be lost.

25 The bolt 6 has a stop pin 50 projecting from its inner or rear end and there is provided a stop member 51 which is normally located in a position to be engaged by the stop pin 50. This stop pin 50 is of such a length that when the stop member 30 51 occupies its normal position shown in Fig. 7 said stop pin 50 will engage the stop 51 before the bolt 6 has been retracted sufficiently to bring the auxiliary latch 38 into register with the opening 49. The auxiliary latch is, therefore, held in 35 its retracted position by the housing 7, and, when in such retracted position, the pin 45 engages in the notch 44 and thus holds the releasing pin 18 in its retracted position (see Fig. 13). The releasing pin 18 will be held in this position by the 40 engagement of the pin 45 of the auxiliary latch in the notch 44 since said auxiliary latch is held in its retracted position by the housing 7. When the pressure on the feeler 27 is released the bolt will move forward under the influence of the 45 spring 19, but the releasing pin 18 will still be held in its retracted position until the releasing latch comes into register with the opening 99, at which time the spring 42 throws the auxiliary latch outwardly, thus allowing the spring 29 to 50 move the feeler and the releasing pin 18 back to their normal positions. This return of the releasing pin 18 to normal position will operate through the cam 24 to force the abutment pin outwardly into its operative position, but at this time the 55 bolt has reached such a position relative to the rack that the abutment pin will assume its operative position on the opposite side of the lip 13 from the plate 14.

The stop 51, however, is a movable stop, and 60 while it is normally in position to be engaged by the stop pin 50, yet when the rack is moved by manipulating the knob, the stop 51 will be withdrawn from a position in which it will be engaged by the stop pin 50. This stop 51 is pivotally 65 mounted at 52 and is acted on by a spring 53 (see Figs. 7 and 8) tending to move it counterclockwise. When the rack 12 is in its normal position shown in Fig. 2 the upper end of the stop 51 engages the side of the rack and is held in its operative 70 position shown in Fig. 7, in which position it is located in the path of movement of the stop pin 50, the latter being shown by dotted lines in Fig. 7.

When the rack is moved backwardly by the 75 knob in order to withdraw the bolt, then as soon

as the toothed part of the rack moves to the rear of the stop 51 and the neck 17 of the rack member comes over the stop, said stop will be thrown forwardly by the spring 53 into the position shown in Fig. 8 and out of the path of movement 10 of the stop pin 50. When the stop 51 is in this position then the bolt can be moved backwardly a sufficient distance to bring the auxiliary latch 38 into register with the opening 49. 54 represents a rest or stop projection which limits the spring- 15 impelled movement of the stop member 51. When the rack is returned to its normal position shown in Fig. 2 the end tooth of the rack has a camming action against the end of the stop 51 and thereby moves it backwardly into the position shown in Fig. 7. 97 indicates a yielding stop (see Fig. 1) having a rounded end and which operates in a recess 96 in the bolt, said stop being acted on by a spring 95. This normally operates in a slot 94 formed in the housing 7 and its purpose is to limit the spring-pressed outward movement of the bolt 6 due to the expansive action of the spring 10. When the bolt 6 is in its latching position shown in Figs. 1 and 2, the stop 97 engages the outer end wall of the slot 94 and thus 20 restrains the bolt from further outward movement.

Although this stop 97 normally holds the latch from moving outwardly beyond the latching position shown in Figs. 1 and 2, yet if outward pressure is applied to the bolt through the rack 12 by turning the knob, the stop 97 will yield backwardly against the action of the spring 95, thus permitting the bolt to be moved forwardly into its deadlocking position shown in Fig. 3.

98 indicates a pin extending outwardly from the bolt and operating in a guiding slot 92 formed in the housing, the purpose of this pin being to prevent the bolt from having any turning movement about its axis.

In the above-described embodiments of the invention the inner and outer knob are axially arranged and the axis of movement of both knobs intersects the axial line of the bolt. In Fig. 11 I have shown an embodiment of the invention 45 where the inner and outer knobs may be placed out of axial alignment. This construction is well adapted for use as a lock for an automobile door or for other locations where it is desirable to have the inside knob and outside knob operating on 50 different axes. In Fig. 11 the housing 7, the bolt 6 operating therein, the spindle 8 having the pinion 11 which meshes with the teeth of the rack 12, and the connection between the rack 12 and the bolt 6 are the same as described 55 with reference to Figs. 1 to 10. In this embodiment of the invention, however, the rack 12 has a rear extension 58 provided with rack teeth 55 that mesh with a pinion 56 carried in a suitable bracket or support 57. The pinion 56 is shown as meshing with another pinion 58 fast on a shaft 59 carried by said bracket 57, and said shaft 59 carries a sprocket wheel 60 which is connected by a sprocket chain 61 to a second sprocket wheel 62 mounted on a spindle 63 that is supported in 65 a second bracket or support 64. The brackets 57 and 64 will be located and concealed in a cavity formed within the door and one of the door knobs may be mounted on the spindle 8 and the other door knob on the spindle 63, in which case the 70 rack 12 can be actuated from either knob in the same way as the rack 12 of Figs. 1 to 10 can be actuated by either knob 9 or 10.

As applied to an automobile door the knob or handle on the outside of the door will preferably 75

be connected to the spindle 8, while the handle on the inside of the door will be connected to the spindle 63. It will be understood, of course, that some usual key-controlled operative connection between the outer knob and the spindle 8 will be employed so that the door may be locked in the usual way.

91 indicates a spring-pressed stop projection carried by the end 90 of the housing 7 and having its inner end operating in a groove 89 formed in the bolt 6, this stop pin being to limit the outward movement of the bolt due to the expansive action of the spring 19. This stop pin 91 is backed by a spring 98 received in a recess in the portion 90 of the housing and the spring is returned in the position by a removable screw plug 97.

I claim:

1. A lock for a door comprising a spring-pressed latching bolt in said door, a spindle extending through the door, knobs for operating said spindle, a pinion on the spindle, a rack meshing with the pinion, a connection between the rack and the bolt which normally prevents backward movement of the bolt relative to the rack, a feeler member exposed at the end of the bolt, and means responsive to pressure applied to the feeler to disrupt the connection between the rack and the bolt.

2. A lock for a door comprising a spring-pressed latching bolt in said door, a spindle extending through the door, knobs for operating the spindle, a pinion on said spindle, a rack meshing with said pinion and having a downturned lip, two abutment members carried by the bolt between which the lip is received, a feeler at the outer end of the bolt, and means responsive to pressure applied to the feeler to withdraw one of said abutment members from operative engagement with the lip.

3. A lock for a door comprising a spring-pressed latching bolt in said door, a spindle extending through the door, knobs for operating the spindle, a pinion on the spindle, a rack meshing with said pinion and having a downturned lip, a plate and an abutment pin carried by the bolt and between which said lip is received, and means for controlling the position of the abutment pin including a part exposed at the end of the bolt, said means being responsive to pressure applied to the exposed part to move the abutment pin into inoperative position out of engagement with the lip.

4. A lock for a door comprising a spring-pressed latching bolt in said door, a spindle extending through the door, knobs for operating the spindle, a pinion on said spindle, a rack meshing with the pinion and having a laterally extending projection, means operatively connecting said projection to the bolt including a plate member and an abutment pin between which said projection is received, a spring acting on the abutment pin and tending to move it into inoperative position, a releasing pin extending axially of the bolt and having a cam portion normally engaging said abutment pin and holding it in its operative position, said releasing pin being movable relative to the bolt into an inoperative position, thus allowing said spring to move the abutment pin simultaneously into its inoperative position, whereby the bolt is free to move backwardly independently of the rack.

5. A lock for a door comprising a spring-pressed latching bolt in said door, a spindle extending through the door in the axial line of the bolt, knobs for operating the spindle, a pinion on the

spindle, a rack meshing with the pinion, operative connections between the rack and the bolt by which movement of the rack in either direction produces a movement of the bolt in a corresponding direction, instrumentalities carried by the bolt and having a portion exposed at the end thereof and rendered operative by the application of pressure to said exposed portion to disrupt said connections, whereby the bolt is free to be moved backwardly against the action of its spring 10 while the rack remains stationary.

6. A lock for a door comprising a spring-pressed latching bolt in said door, a spindle extending through the door in the axial line of the bolt, knobs for operating the spindle, a pinion on the 15 spindle, a rack meshing with the pinion, and operative connections between the rack and the bolt by which movement of the rack in one direction will withdraw the bolt and in the other direction will move the bolt into locking position, a feeler exposed at the outer end of the bolt, and means responsive to pressure applied to the feeler to disrupt such operative connection.

7. A lock for a door comprising a spring-pressed latching bolt in said door, a spindle extending through the door, knobs for operating the spindle, a pinion on said spindle, a rack meshing with said pinion and having a downturned lip, two abutment members carried by the bolt between which the lip is received, a feeler movably carried by the outer end of the bolt, and means rendered operative by movement of the feeler relative to the bolt to withdraw one of said abutment members from operative engagement with the lip.

8. A lock for a door comprising a spring-pressed latching bolt in said door, a spindle extending through the door, knobs for operating the spindle, a pinion on the spindle, a rack meshing with the pinion and having a laterally extending projection, two abutment members carried by the bolt 40 and between which said projection is received, a feeler pivoted to the end of the bolt, a spring acting on the feeler and normally holding it projecting beyond the bolt end, and means rendered operative by depressing the feeler to withdraw 45 one of the abutment members from engagement with said projection whereby the bolt may be retracted within the door while the rack remains stationary.

9. A door lock for a door comprising a spring-pressed latching bolt in said door, a spindle extending through the door, knobs for operating the spindle, a pinion on the spindle, a rack meshing with the pinion and operatively connected to the bolt, a feeler movably carried by the outer 55 end of the bolt, and means rendered operative by movement of the feeler relative to the bolt to disrupt said connection between the rack and the bolt.

10. A lock for a door comprising a spring-pressed latching bolt in said door, a tubular housing in the door in which the bolt operates and by which it is guided, said housing having the same cross-sectional shape as that of the bolt and fitting the latter, an auxiliary latch carried 65 by the bolt and having interlocking engagement with the housing when the bolt is in latching position, which interlocking engagement prevents backward movement of the bolt regardless of whether the door is open or closed, a spindle, operative connections between the spindle and the bolt, and means to retract the auxiliary latch during the initial turning movement of the spindle in a direction to withdraw the bolt.

11. A lock for a door comprising a spring-75

pressed bolt, a housing in the door in which said bolt operates, said bolt normally being in latching position but being movable forwardly beyond latching position into locking position, an auxiliary latch carried by the bolt and having interlocking engagement with the housing when the bolt is in latching position and having interlocking engagement with the striker plate in the door frame when the bolt is projected forwardly beyond the latching position into locking position, a spindle, operative connections between the spindle and the bolt, and means to retract the auxiliary latch during the initial turning movement of the spindle in a direction to withdraw the bolt from either locking position or latching position.

12. A lock for a door comprising a spring-pressed latching bolt, a housing in said door in which the bolt operates, an auxiliary latch carried by the bolt and having interlocking engagement with the housing when the bolt is in latching position, a spindle for operating the bolt, a pinion on the spindle, a rack meshing with the pinion and operatively connected to the bolt, a feeler carried by the bolt at its outer end, means rendered operative by the depression of the feeler to disrupt said connection between the rack and the bolt, and means also rendered operative by the depression of the feeler to retract the auxiliary latch.

13. A lock for a door comprising a spring-pressed latching bolt, a housing in the door in which the bolt operates, an auxiliary latch carried by the bolt and having interlocking engagement with the housing when the bolt is in latching position, a spindle for operating the bolt, a pinion on said spindle, a rack meshing with said pinion and having a downturned lip, two abutment members carried by the bolt between which the lip is received, a feeler carried by the bolt at its end, means rendered operative by depression of the feeler to withdraw one of said abutment members from operative engagement with the lip, and means also rendered operative by the depression of the feeler to retract the auxiliary latch.

14. A lock for a door comprising a spring-pressed latching bolt, a housing in said door in which the bolt operates, an auxiliary latch carried by the bolt and having interlocking engagement with the housing when the bolt is in latching position, a spindle for operating the bolt, a pinion on said spindle, a rack meshing with said pinion and having a downturned lip, two abutment members carried by the bolt between which the lip is received, a feeler carried by the bolt at its end, a plurality of devices rendered operative by depressing the feeler, one device operating to withdraw one of the abutment members from operative engagement with the lip and the other device operating to retract said auxiliary latch.

15. A lock for a door comprising a spring-pressed latching bolt, a housing in the door in which the bolt operates, said housing having a recess, an auxiliary latch carried by the bolt and normally occupying said recess when the bolt is in latching position, a spindle for operating the bolt, a pinion on said spindle, a rack meshing with said pinion and having a downturned lip, two abutment members carried by the bolt between which the lip is received, a feeler carried by the bolt at its outer end, and a plurality of devices rendered operative by movement of the feeler relative to the bolt, one device operating to withdraw one of said abutment members from op-

erative engagement with the lip and the other device operating to withdraw the auxiliary latch from the recess in the housing.

16. A lock for a door comprising a spring-pressed latching bolt in the door, a housing within the door having a shape to fit the bolt and by which the bolt is guided, said bolt normally having a latching position but being movable backwardly into the housing, a spindle for operating the bolt, a pinion on the spindle, a rack meshing with the pinion and having a down-turned lip, two abutment members carried by the bolt between which the lip is received, the front abutment member being movable from operative to inoperative position, a feeler exposed at the end of the bolt, an auxiliary latch carried by the bolt and having interlocking engagement with the housing when the bolt is in latching position, a releasing pin carried by the bolt and connected to the feeler, means to move the auxiliary latch into inoperative position by movement of the releasing pin when the feeler is depressed, thereby permitting the bolt to be retracted within the housing, means to move the front abutment into its inoperative position when the feeler is depressed, thereby permitting the bolt to move backwardly independently of the rack, said auxiliary latch being held in its inoperative position by the housing when the bolt is retracted, and means carried by the auxiliary latch and acting on the releasing pin to hold it in its retracted position while the auxiliary latch is in its inoperative position whereby the movable abutment will be maintained in its retracted position until the bolt is returned to its latching position.

17. A lock for a door comprising a spring pressed latching bolt, a housing in the door in which the bolt slides, said housing having a front and a rear recess, a spindle for operating the bolt, a pinion on the spindle, a rack meshing with the pinion and having a down-turned lip, two abutment members carried by the bolt between which the lip is received, the front abutment member being movable from operative to inoperative position, an auxiliary latch carried by the bolt and movable transversely thereof, said auxiliary latch occupying one of the recesses in the housing when the bolt is in latching position and occupying the other recess when the bolt has been fully retracted by the spindle, a feeler exposed at the end of the bolt, a releasing pin connected to the feeler and slidable longitudinally of the bolt, means cooperating with the releasing pin to move the movable abutment into inoperative position when the releasing pin is moved by depression of the feeler, means to retract the auxiliary latch by such movement of the releasing pin whereby the bolt is free to move backwardly independently of the rack when the pressure is applied to the feeler, a stop pin carried by the bolt and a stop member cooperating with said stop pin to prevent complete backward movement of the bolt sufficient to bring the auxiliary latch into alignment with the rear recess and means cooperating with the retracted auxiliary latch to hold the releasing pin in its retracted position until the bolt again is moved forwardly to latching position.

18. A lock for a door comprising a spring pressed latching bolt, a housing in the door in which the bolt slides, said housing having a front recess and a rear recess, a spindle for operating the bolt, a pinion on the spindle, a rack meshing with the pinion and having a down-turned lip, two abutment members carried by the bolt be-

- 5 between which the lip is received, the front abutment member being movable from operative to inoperative position, an auxiliary latch carried by the bolt and movable transversely thereof, said auxiliary latch occupying the front recess in the housing when the bolt is in latching position and occupying the rear recess when the bolt has been fully retracted by the spindle, a feeler exposed at the end of the bolt, a releasing pin connected to the feeler and slidable longitudinally of the bolt, means cooperating with the releasing pin to move the movable abutment into inoperative position when the releasing pin is moved by depression of the feeler, means to retract the auxiliary latch by such movement of the releasing pin, whereby the bolt is free to move backwardly independently of the rack when the pressure is applied to the feeler, a stop pin carried by the bolt and a stop member cooperating with said stop pin to prevent complete backward movement of the bolt sufficient to bring the auxiliary latch into alinement with the rear recess, and means cooperating with the retracted auxiliary latch to hold the releasing pin in its retracted position until the bolt again is moved forwardly to latching position, said stop being rendered inoperative when the bolt is retracted by the spindle.

19. A lock for a door comprising a spring pressed latching bolt in said door, a spindle for operating the bolt, a pinion on said spindle, a rack meshing with said pinion and having a down-turned lip, a front and rear abutment member carried by the bolt between which the lip is received, a feeler movably carried by the outer end of the bolt, means rendered operative by movement of the feeler relative to the bolt to withdraw the front abutment member from operative engagement with the lip, thereby to permit the bolt to be retracted into the door while the rack remains stationary, and means cooperating with the housing to insure the retention of the retracted abutment member in its retracted position until the bolt has again moved forward into latching position.
20. A lock for a door comprising a spring pressed latching bolt, a housing in the door in which the bolt slides, said housing having a front recess and a rear recess, a manually operable spindle, a rack connected thereto for operating the bolt, normally operative connections between the spindle and the bolt, an auxiliary latch carried by the bolt and movable transversely thereof, said auxiliary latch occupying the front recess in the housing when the bolt is in latching position and occupying the rear recess when the bolt has been fully retracted by the spindle, a feeler exposed at the end of the bolt, a releasing pin connected to the feeler and slidable longitudinally of the bolt, means cooperating with the releasing pin to disrupt the connections between the spindle and the bolt when said releasing pin is moved by depression of the feeler, means to retract the auxiliary latch by such movement of the releasing pin whereby the bolt is free to move backwardly independently of the rack when pressure is applied to the feeler, a stop pin carried by the bolt, and a stop member normally held in operating position by the rack and cooperating with said stop pin to prevent backward movement of the bolt sufficient to bring the auxiliary latch into alinement with the rear recess, said stop being rendered inoperative when the rack is manually moved by the spindle.
21. A lock for a door comprising a spring-pressed latching bolt normally occupying a latching position but movable forwardly beyond latching position into a locking position, a housing in the door in which said bolt operates, said housing having the same cross-sectional shape as the bolt and fitting the latter and also having a recess, an auxiliary latch carried by the bolt, said latch, when the bolt is in latching position, having a locking engagement with the recess of said housing which prevents backward movement of the bolt but which permits forward movement thereof both while the door is opened and while it is closed, a spindle, operative connections between the spindle and the bolt by which the bolt may be moved from latching to locking position, and means actuated by the initial turning movement of the spindle in a direction to withdraw the bolt from either position to retract the auxiliary latch.

JOSEPH H. MILLIGAN.
